UNITED STATES PATENT OFFICE.

LAFAYETTE SAMS, OF NEAR WOLCOTTVILLE, INDIANA.

FENCE.

SPECIFICATION forming part of Letters Patent No. 355,217, dated December 28, 1886.

Application filed July 22, 1886. Serial No. 208,736. (No model.)

To all whom it may concern:

Be it known that I, LAFAYETTE SAMS, a citizen of the United States, residing near Wolcottville, in the county of Lagrange and State of Indiana, have invented a certain new and useful Improvement in Portable Fences, of which the following is a specification.

My invention relates to improvements in portable fences in which each panel is made separate; and the objects of my improvements are, first, to provide a cheap, light, and substantial fence without much wood and having an iron post-support, thus preventing the wood from touching the ground and decaying, and having adjustable connections for holding the panels together. I attain these objects by the devices illustrated in the drawings, in which—

Figure 1 shows a perspective view of one panel of the fence as set up. Fig. 2 is a detail of the post-support as detached from fence.

Similar letters refer to similar parts.

Each panel consists of two boards, *a A*, one post, *B*, two upright stays, *C C*, with wire strands *D D D D*, and hooks *e E*. The post *B* has two gains cut to receive boards *a A*. The stays *C C* are fastened transversely to boards *a A*, as shown in Fig. 1. The stay farthest from post *B* is set a short distance from the ends of boards *a A* to allow them to lap on the post at the end of the next panel, where there are two hooks, *e E*, to receive them. The top hook, *e*, goes through the post *B* and has a nut on its back to tighten upon and clamp the top board when the fence is set up, so as to firmly hold it in position. The bottom

board has a notch, *i*, to set in hook *E*. The wires *D D D D* are stretched and fastened to post *B* and stays *C C*.

The post-support consists of a piece of iron, *F*, curved edgewise, with eyes *j j* for pins *g g*. The curve in piece *F* causes the pins *g g* to set at an angle inward, thus preventing the fence from moving them, yet permitting them to be easily drawn by hand or lever. The braces *h h* extend from near ends of bar *F* to post *B*, where they are bolted or screwed fast.

I am aware that prior to my invention movable fences have been made, and that similar boards and stays have been used on gates and fences, but am not aware of their being applied to a fence of this description. I therefore do not claim such a combination, broadly; but

What I do claim as my invention, and desire to secure by Letters Patent, is—

The portable fence-panel composed of the end post, *B*, with hooks *e E*, the cross-stays *C C*, and the top and bottom bars, *a A*, connected to the post and stays and extending beyond the end stay, and having notch *i*, and the intermediate wire strands, *D*, in combination with the braced support consisting of bar *F*, with inclined or triangular braces *h*, and pins or stakes *g g*, substantially as and for the purpose described.

LAFAYETTE SAMS.
